UNITED STATES PATENT OFFICE.

MILES J. LAWLER, OF DENVER, COLORADO.

DOOR-CHECK.

1,297,189.

Specification of Letters Patent. Patented Mar. 11, 1919.

Application filed August 16, 1918. Serial No. 250,103.

To all whom it may concern:

Be it known that I, MILES J. LAWLER, a citizen of the United States, residing at the city and county of Denver and State of Colorado, have invented certain new and useful Improvements in Door-Checks; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to that type of door check which is secured to the door. The object thereof is to provide such a device which will be simple, efficient, cheap to manufacture and will automatically return to 20 inoperative position.

Briefly, the invention comprises a block to be secured to the door and a wedge connected to the block by a spring controlled link which will automatically return the wedge to inoperative position when the door is moved sufficiently to free the wedge. There is a compensating connection between the wedge and the link to permit limited 25 relative movement of the wedge horizontally. In the drawings:

30 Figure 1 is a side elevation of the device applied to a door, the wedge and link being shown in operative position in dashed lines.

Fig. 2 is a front elevation indicated by line 2—2 of Fig. 1.

35 Fig. 3 is a vertical section on line 3—3 of Fig. 2, the door being omitted.

Fig. 4 is a horizontal section on line 4—4 of Fig. 3.

40 Figs. 5 and 6 are sections taken on the lines 5—5 and 6—6 respectively of Fig. 3.

The check comprises a door block 10, a link 20 and a wedge 30.

The block 10 is provided with an elongated slot 15 and a hole 16 through which screws are passed to secure the block to a door B. The block is channeled out at 17 to receive the link 20 and is provided with side walls 18 to receive the wedge 30.

45 The lower end of link 20 is mounted in the block 10 by means of a pintle 21 about which a spring 22 is mounted, the loop of the spring seating in a recess 23 in the link and the ends 24 of the spring being embedded in the block 10.

50 The upper end of the link 20 is offset at

25 and extends through a slot in the wedge 30 between the walls 31 thereof. This slot is enlarged into an interior pocket 32 in which a reciprocating plunger 33 is located. 60 The plunger has a recess 34 in one side thereof into which the offset end 25 of link 20 extends and in which it is pivotally mounted by pintle 35. The plunger has a reduced extension 36 which reciprocates in 65 an apertured closure 37 fixed in the end of the pocket 32. A compression spring 38 is mounted on the extension 36 and its engagement between the closure 37 and a shoulder on the plunger 33 tends to maintain the plunger in the retracted position 70 shown in Fig. 3.

When it is desired to use the check the operator presses upon the top of the wedge 30 forcing it down and outward against 75 the tension of the spring 21 until it is placed in position upon the floor as indicated in Fig. 1. The door is then moved in the direction of the arrow a, Fig. 1, to secure the wedge, this motion being permitted by movement of the plunger 33 against the spring 38. To release the device the door is moved in a direction opposite to that indicated by arrow a, whereupon the springs 21 and 38 restore the parts to their 80 normal positions as indicated in full lines in Figs. 1, 2 and 3.

In positioning the check on the door, the check is given an approximately correct position and a screw is then inserted in the slot 90 15 and partially screwed in. The check is then accurately positioned for proper operation of the wedge and the screw tightened. To positively retain the check in final position a screw is inserted in hole 16. 95

I claim:

1. A door check comprising a spring-controlled link adapted to be pivotally connected at one end with a door, a wedge movably connected with the other end of 100 the link and a spring controlling the connection between the wedge and the link.

2. A door check comprising a spring-controlled link adapted to be pivotally connected at one end with a door, a wedge, and 105 a spring-controlled plunger therein, the other end of said link being pivotally connected with said plunger, said parts being normally held in collapsed relation.

3. A door check comprising a block adapted to be secured to a door, a spring controlled link pivotally connected at one end

- with said block and normally held thereagainst, a wedge, and a spring controlled plunger therein, the other end of said link being pivotally connected with said plunger.
- 5 4. A door check comprising a block adapted to be secured to a door, a spring-controlled link pivotally connected at one end with said block, a wedge, and a movable spring controlled connection between said 10 wedge and the other end of said link.
5. A door check comprising a block adapted to be secured to a door, a spring-controlled link pivotally connected at one end with said block, a wedge having a pocket 15 therein and a slot communicating with said pocket, and a plunger in said pocket, the other end of said link being pivotally connected with said plunger.
6. A door check comprising a block adapted to be secured to a door and having a screw slot therein for adjusting the check on the door, a spring-controlled link pivotally connected at one end with said block, a wedge,
- 20 and a pivotal spring controlled connection between the other end of the link and the wedge.
7. A door check comprising a block adapted to be secured to a door having a screw slot therein for adjusting the check on the door, and a screw hole therein, a spring-controlled link pivotally connected at one end with the block, a wedge, and a movable pivoted spring controlled connection between said wedge and the other end of said link.
8. A door check comprising a block adapted to be secured to the door, a spring-controlled link pivotally connected at one end with the block, a wedge, a connection between the other end of the link and the wedge permitting pivotal motion therebetween, and a spring controlling the connection last named to restore the normal inoperative relation between the link and the wedge when the wedge is released.
- 30 40
- In testimony whereof I affix my signature. 45
- MILES J. LAWLER.
